WRAPPING PAPER OR SIMILAR ARTICLE

Walter L. Wolf, Philadelphia, Pa., assignor to Wolf Brothers, Inc., Philadelphia, Pa., a corporation of Pennsylvania

Application April 30, 1954, Serial No. 30,286

Term of patent 14 years

(Cl. D59—5)

The figure is a plan view of a wrapping paper or similar article showing my new design, a unit being enclosed within the broken lines and repeated as indicated by the extensions beyond the unit boundaries.

I claim:

The ornamental design for a wrapping paper or similar article, as shown and described.
